By Luther Johnson Atty.

UNITED STATES PATENT OFFICE.

DAVID RUSSAKOV, OF CHICAGO, ILLINOIS.

HASP AND STAPLE DEVICE.

Application filed February 21, 1921. Serial No. 446,717.

To all whom it may concern:

Be it known that I, DAVID RUSSAKOV, a citizen of the United States, residing at Chicago, Cook county, Illinois, have invented certain new and useful Improvements Relating to Hasp and Staple Devices, and of which the following is a specification.

The principal object of these improvements is to provide a simple form of hasp-and-staple device according to which the hasp may be readily applied to and released from the staple as desired, and be effectively held upon the staple, by a self-contained hand-operable member, while maintaining the capacity of the staple for holding a separable locking device, such as a padlock, for securing the hasp-and-staple in locked relation. The device herein disclosed and as hereinafter claimed is an improvement upon the structure of my copending application, Serial No. 339,195, filed November 19, 1919, and according to the present improvements the hasp is maintained upon the staple element more effectively and with greater security against the accidental separation of the parts when the shipping boxes, to which in my practice these devices are applied, are rolled and tumbled about in transit.

In the accompanying drawings, forming a part of this specification, Figure 1 is a face view of the device in its locked condition; Fig. 2 is a medial longitudinal section of the hasp and locking element and a side view of the hasp showing the operation of applying or removing the hasp; Fig. 3 is a face view of the hasp member; and Fig. 4 is a face view of the staple and locking element thereon.

The hasp 10 having the butt 11 and the hinge 12 is shown according to well known form. The hasp is provided with a relatively long and narrow slot-like opening 13 adapted to receive the staple in the usual way. The staple 14 is shown in this instance as a metal stamping, and its projecting part is of substantially rectangular formation.

The ring-like locking element 16 is permanently held upon the staple 14 when the device is in use, the element 16 being preferably oblong as shown. In one of the inner side walls of the ring 16 a transverse recess or notch 17 is formed, and on the underside of the top part of the staple a

transverse ridge, lug or extension 18 is formed, as by spot-welding a piece of metal thereon. The staple 10 is provided with a transverse slot 19 in the form of lateral extensions or enlargements of the staple-receiving slot 13, and in the preferred embodiment the transverse slot 19 is at an angle which departs materially from the right angular relation of the similar transverse slot shown in my said copending application. The angle shown is acute forty-five degrees or obtuse one hundred and thirty five degrees. The width of the transverse slot 19 is such as to permit the locking element 16 to pass through it bodily, and its length is such as, in the preferred oblong embodiment of the ring shown, to permit the ring 16 to pass through it only when the ring is directed therethrough.

From the construction described it will be clear that when the parts are in their locked relation as shown by Fig. 1, the ring 16 will hang downward in its longitudinal direction as shown and will be prevented by the projection 18 from moving normally upward or into a position for entering the transverse slot. If, however, the ring 16 be turned partially around so that the notch 17 therein will register with the projection 18 the ring may be passed beyond the projection 18. If then the ring 16 be again turned so as to direct one of its ends through the slot 19 the ring may pass bodily through the transverse slot when the hasp 10 is lifted away from the staple device.

When it is desired to replace the hasp upon the staple device the ring 16 is first pointed endwise toward the slot 19, the staple being moved toward the hasp with the ring passing through the slot, after which the ring is turned so that the notch 17 again registers with the projection 18. Thereupon the ring may be passed into the normally lower or end portion of the staple and on allowing it to fall it naturally assumes the up-and-down position shown in Fig. 1.

There are several distinct features of improvement herein disclosed and they may all be combined in one device as illustrated, or they may be used separately with notable advantage.

One of these features is the provision of a transverse slot which is not at right angles to the longitudinal direction of the staple

receiving slot, but is at such a material variation from the right-angular arrangement as to call for a special movement of the ring before being passed through the slot. The invention in this respect might well be applied with notable advantage to a hasp-and-staple device otherwise in accordance with what is shown in my said copending application.

10 Another feature of improvement is a ring-restraining or locking device, for instance the lug or projection 18 on the staple and the cooperating recess 17 on the ring. With this feature of improvement in a hasp-and-staple device notable advantage would be had even though the transverse slot through which the ring passes be at a right angle or at some other angle than the particular one shown.

15 20 A third feature of improvement is the oblong form of the ring 16 whereby it is normally maintained in such position as to keep the notch 17 out of registration with the lug 18.

25 I contemplate various changes and modifications from what is specifically herein shown, as being within the scope of the invention herein set forth, and as indicated in the appended claims.

30 I claim:

1. A hasp-and-staple device comprising a staple, a hasp having a slot-like opening therethrough for the staple, a ring-like hasp-locking element loosely held on the staple, the hasp having a transverse slot forming substantially oppositely-disposed recesses extending from said slot-like opening for the staple, said transverse slot being at an angle which has a materially great departure from a right angle with respect to the direction of the opening for the staple and having such width and length that the ring-like member may pass therethrough when releasing or applying the hasp to the staple.

2. A hasp-and-staple device comprising a 45 staple, a hasp having a slot-like opening therethrough for the staple, a ring-like hasp-locking element loosely held on the staple, the hasp having a transverse slot forming substantially oppositely-disposed recesses 50 extending from said slot-like opening, said transverse slot being at an angle which has a materially great departure from a right angle with respect to the direction of the opening for the staple and having such 55 width and length that the ring-like member may pass therethrough when releasing or applying the hasp to the staple, and cooperating ring-locking means on the ring and on the staple for maintaining the ring 60 against movement into a position for entering said oppositely-disposed recesses in the hasp-releasing operation except when the ring is in a given position with respect to the staple. 65

3. A hasp-and-staple device comprising a staple, a hasp having a slot-like opening therethrough for the staple, a ring-like hasp-locking element loosely held on the staple, the hasp having a transverse slot 70 forming substantially oppositely-disposed recesses extending from said slot-like opening, said transverse slot having such width and length that the ring may pass therethrough when releasing or applying the 75 hasp to the staple, the staple having a projection on its underside in the path of movement of the ring on the staple, the ring having a reduced portion adapted to be registered with said projection to permit the ring 80 to move past the projection, the transverse slot in the hasp being positioned with respect to the position of said projection whereby the ring must pass beyond the projection in the hasp-releasing operation before it can enter the transverse slot. 85

DAVID RUSSAKOV.
